HOUSING FOR AN ANAMORPHOSER

Robert E. Gottschalk and John R. Moore, Los Angeles,
Calif., assignors to Panavision, Inc., a corporation of
California

Application July 9, 1954, Serial No. 31,354

Term of patent 14 years

(Cl. D57—7)

FIG. 1.

FIG. 2.

FIG. 4.

FIG. 3.

FIG. 5.

Figure 1 is a top plan view of the housing for an anamorphoser embodying our design;

Fig. 2 is a side elevational view as seen in the direction of the arrow 2 of Fig. 1;

Fig. 3 is a bottom plan view;

Fig. 4 is a front elevational view taken along the arrow 4 of Fig. 2; and

Fig. 5 is a back elevation view taken along the arrow 5 of Fig. 2.

The dominant feature of our design resides in the portions shown in full lines.

We claim:

The ornamental design for a housing for an anamorphoser, as shown and described.
